(57) **CLAIM**

The ornamental design for an electrical module outlet, as shown and described.

DESCRIPTION

FIG. 1 is a perspective view of an electrical module outlet embodying the present invention;

FIG. 2 is a side elevational view of the electrical module outlet;

FIG. 3 is a front elevational view of the electrical module outlet;

FIG. 4 is a top plan view of the electrical module outlet; and, FIG. 5 is a bottom plan view of the electrical module outlet. In the drawings, the broken lines are for the purpose of illustrating environment only and form no part of the claimed design.
